(57) **CLAIM**

The ornamental design for a combination ceiling fan and light fixture, as shown and described.

DESCRIPTION

FIG. 1 is a perspective view from below of a combination ceiling fan and light fixture in accordance with my design;

FIG. 2 is a reduced top plan view of the combination ceiling fan and light fixture in accordance with my design;

FIG. 3 is a greatly reduced bottom plan view of the combination ceiling fan and light fixture in accordance with my design;

FIG. 4 is an enlarged front elevation view of the combination ceiling fan and light fixture in accordance with my design, the opposite view being a mirror image of that shown except for the positioning of the fan blades; and,

FIG. 5 is a slightly enlarged side elevation view of the combination ceiling fan and light fixture in accordance with my design, the opposite view being a mirror image of that shown except for the positioning of the fan blades.
